UNITED STATES PATENT OFFICE

2,680,977

CROSS-OVER DEVICE FOR ROD MILL
REPEATERSFrank J. Artac, Jr., Joliet, Ill., assignor to United
States Steel Corporation, a corporation of New
Jersey

Application April 11, 1952, Serial No. 281,925

4 Claims. (Cl. 80—52)

1

This invention relates to improvements in rod mill repeaters, and particularly to a cross-over device for carrying rods across the troughs of a repeater to a loop run-out floor.

In multi-strand continuous rod mills the last few roll stands often are situated side by side. In the operation of such a mill, the leading end of each rod must be looped back from the exit end of the first roll stand into the entry end of the succeeding stand. The elongation which the two roll stands produce in the rod elongates the loop considerably before its trailing end emerges from the first stand, and it is usual to provide a run-out floor between the roll stands for supporting this loop. Modern mills are equipped with repeaters which comprise a series of semicircular troughs at the end of the run-out floor adjacent the two roll stands. One of these troughs receives each rod as it emerges from the first roll stand and automatically loops it around so that it can enter the succeeding stand. Subsequently the loop jumps out of the top of the trough and builds up on the portion of the run-out floor beyond the repeater. One difficulty in operating such mills is that loops jumping from the inner troughs of the repeater sometimes drop into one of the outer troughs and become snarled. Usually rods overlap, and if a loop drops into a trough which is carrying the leading end of another rod, a cobble can form.

An object of the present invention is to provide, in combination with a rod mill repeater, a cross-over device which allows rod loops to jump freely out of their troughs but prevents their dropping into other troughs.

A further object is to provide a cross-over device of simple construction which can be installed on existing repeaters with only minor alterations therein.

In accomplishing these and other objects of the invention, I have provided improved details of structure, a preferred form of which is shown in the accompanying drawing, in which:

Figure 1 is a diagrammatic top plan view of a portion of a rod mill, the repeater of which is equipped with a cross-over device embodying features of the present invention;

Figure 2 is a top plan view on a larger scale of a portion of the repeater;

Figure 3 is a vertical sectional view on a still larger scale taken on line III—III of Figure 2; and

Figure 4 is a vertical sectional view taken on line IV—IV of Figure 3.

Figure 1 shows diagrammatically a portion of a

2

multi-strand rod mill that comprises two roll stands 10 and 12 situated side by side, a run-out floor 13 between said stands, and a repeater 14 for carrying rods R from stand 10 to stand 12. The roll stands provide several alternative passes for the rods, in this instance four, and the repeater has a corresponding number of troughs 15, 16, 17 and 18, which are approximately semicircular in plan and extend from the exit end of stand 10 to the entry end of stand 12. After one of the repeater troughs carries a rod between the stands, the loop in the rod commences to elongate and jumps out of the trough on to the portion 13a of the run-out floor 13 beyond the repeater. When rods jump out of any of the inner troughs 15, 16 and 17, they must cross one or more other troughs before reaching this portion of the run-out floor. According to the present invention, the three outer troughs 16, 17 and 18 are equipped with cross-over devices 19 (Figure 2), which prevent rods R dropping into these troughs as they cross, and yet do not interfere with a rod as it jumps out of its own trough.

Figures 3 and 4 show on a larger scale one set of the cross-over devices 19. At the location of these devices the walls of the troughs have an enlarged cross-section and flare upwardly, as indicated at 20, and the upper faces of these walls slope inwardly. The enlargements in the walls contain vertical bores 21. Each cross-over device 19 comprises a rod bent to inverted L-shape and providing vertical and horizontal arms 22 and 23. The vertical arms 22 are rotatably received in bores 21. Torsion springs 24 encircle the lower ends of arms 22 and urge the cross-over devices to a position where their horizontal arms 23 bridge the trough. The upper face of each of the walls between troughs is cut away, as indicated at 25 (Figure 4), to enable the cross-over devices to pivot forwardly against the action of their springs 24 and to form a stop 26 which the horizontal arm 23 engages to limit the rearward position of the device.

I find it is necessary to employ only two sets of these cross-over devices for each repeater. One such set is located just beyond the points where the loops jump out of the repeater troughs. The second set is located about 30° beyond the first set. Nevertheless it is apparent that additional sets of cross-over devices could be used if desired.

In operation, as a rod R jumps out of any of the inner troughs 15, 16 or 17 to the portion 13a of floor 13 beyond the repeater, it rides on the horizontal arms 23 of the cross-over devices 19

as it crosses the outer troughs. These cross-over devices thus prevent the rod from dropping into one of the outer troughs. When a rod jumps out of one of the troughs 16, 17 or 18 which is equipped with a cross-over device, the force of the rod against the horizontal arm 23 pivots the device forwardly against the action of its spring 24. Thus the rod moves easily out of its trough without interference.

From the foregoing description it is seen that the present invention affords a cross-over device of exceedingly simple construction and yet fully effective for preventing rods dropping into repeater troughs as they cross. This device can be installed on existing repeaters with but minor alterations.

While I have shown and described only a single embodiment of the invention, it is apparent that modifications may arise. Therefore, I do not wish to be limited to the disclosure set forth but only by the scope of the appended claims.

I claim:

1. The combination, with a rod mill repeater having outward and inward troughs and an up-standing wall therebetween, said troughs being upwardly open and approximately semicircular in plan, of a cross-over device comprising an arm mounted on said wall for pivotal movement on a vertical axis and adapted to bridge said outward trough, and yieldable means normally holding said arm in its bridging position but permitting said arm to pivot forwardly in the direction of rod travel out of the way of rods leaving said outward trough.

2. The combination, with a rod mill repeater having outward and inward troughs and an up-standing wall therebetween, said troughs being upwardly open and approximately semicircular in plan, of a cross-over device comprising an arm pivoted to said wall for movement on a vertical axis and adapted to bridge said outward trough, and a spring connecting said arm and said repeater and normally holding said arm in its bridging position, but being yieldable to permit said arm to pivot forwardly in the direction

4
of rod travel out of the way of rods leaving said outward trough.

3. The combination, with a rod mill repeater having outward and inward troughs and an up-standing wall therebetween, said troughs being upwardly open and approximately semicircular in plan, of a cross-over device comprising an arm pivotally mounted on said wall and adapted to turn on a vertical axis and having a position in which it bridges said outward trough, a stop formed on said wall on the rearward side of said arm and with which said arm is engageable in its bridging position, and a spring connecting said arm and said repeater and urging said arm rearwardly into engagement with said stop, but being yieldable to permit said arm to pivot forwardly away from said stop and in the direction of rod travel out of the way of rods leaving said outward trough.

4. The combination, with a rod mill repeater having outward and inward troughs and an up-standing wall therebetween, said troughs being upwardly open and approximately semicircular in plan, of a cross-over device comprising an arm pivoted to said wall beyond the point where rods normally move out of the troughs and adapted to turn on a vertical axis and having a position in which it bridges said outward trough, a stop formed on said wall on the rearward side of said arm and with which said arm is engageable in its bridging position, and a spring connecting said arm and said repeater and urging said arm rearwardly into engagement with said stop, but being yieldable to permit said arm to pivot forwardly away from said stop and in the direction of rod travel to move out of the way of rods leaving said outward trough.
